UNITED STATES PATENT OFFICE.

SAMUEL G. WILKERSON, OF DURANGO, COLORADO.

DESIGN FOR A CURTAIN AND SHADE BRACKET.

SPECIFICATION forming part of Design No. 31,791, dated November 7, 1899.

Application filed October 16, 1899. Serial No. 733,833. Term of patent 7 years.

To all whom it may concern:

Be it known that I, SAMUEL G. WILKERSON, a citizen of the United States, residing at Durango, in the county of La Plata and State of Colorado, have invented and produced a new and original Design for Curtain and Shade Brackets; and I do hereby declare the following to be a full, clear, and exact description of the invention, such as will enable others skilled in the art to which it appertains to make and use the same.

The design herein illustrated is for a curtain and shade bracket—that is, for a bracket designed to support both a curtain-pole and shade-pole.

The distinguishing feature of the design is the combination of a curved arm and vertical arm with a common shank. The curved arm is at the extremity, while the vertical arm is approximately about the center—that is, between the shank and the curved arm.

The drawing is a perspective view of the bracket.

1 is the curved arm.

2 and 3 are the opposite ends of the curved arm.

4 is the depending vertical arm, having a perforation 5.

6 is the shank, having an enlargement or boss 7, which carries the attaching-screw 8.

In this illustration the perforation is shown rectangular as an example.

What I claim is—

The design for a curtain and shade bracket, substantially as shown and described.

In testimony whereof I have signed my name to this specification in the presence of two subscribing witnesses.

SAMUEL G. WILKERSON.
